UNITED STATES PATENT OFFICE

HAROLD BATCHELOR, OF JERSEY CITY, NEW JERSEY

VANITY CASE

Application filed October 2, 1931. Serial No. 566,426.

This invention relates to a vanity case and more particularly to a vanity case adapted to contain a cosmetic, such as face powder, in a loose form.

An object of the invention is to construct the case in such manner that the powder will be unable to spill or leak therefrom.

Another object is to so construct the case that it will embody means by which the user may be enabled to remove for each application the desired quantity of powder from the case to suit individual requirements.

Another object is to provide simple and easily operated means to remove excess powder from the powder puff employed.

A further object is to arrange the various parts in such manner that the case will be of a neat and attractive appearance both inside and out.

Other objects and aims of the invention, more or less specific than those referred to above, will be in part obvious and in part pointed out in the course of the following description of the elements, combinations, arrangements of parts and applications of principles constituting the invention; and the scope of protection contemplated will be indicated in the appended claims.

In the accompanying drawing which is to be taken as a part of this specification, and in which I have shown merely a preferred form of embodiment of the invention:

Figure 1 is a cross section through the case embodying the invention and showing the case closed, and

Fig. 2 is a plan view showing the case opened and with the puff portion partly broken away.

Referring to the illustrative embodiment shown in the drawing, the vanity case is preferably formed with a cupped lid 10 hinged as at 12 to a similarly cupped base 14.

The lid portion 10 and base portion 14 are, in the preferred embodiment, both of circular contour, but it will be understood that other shapes may be used without departure from the spirit of the invention.

The lid 10 and base 14 are preferably of similar size so that the cupped edges thereof meet as at 16 in abutting relation.

The lid 10 contains the usual mirror 18 which is retained in position by an annular member 20 secured to the inner side of the cupped edge of the lid 10.

The base 14 is constructed to receive and support the powder puff 22 which is arranged for removal from the case as desired.

The puff 22 has the outer marginal portion of its upper surface 24 engaging the annular member 20 of the lid.

The outer annular portion of the lower surface 26 of the puff 22 engages one leg as 23 of a circular angle member 30, the other leg as 24 of which member is secured to the inner side surface of the base 14 and has a portion projecting beyond the abutting edges 16 and telescoping into the lid 10 where it engages the annular member 20 when the lid 10 is closed.

In this manner the puff 22 is gripped by its annular marginal portion between the leg 23 of the angle member 30 and the annular member 20 of the lid when the lid is closed.

The interior of the case is sealed by the projecting leg 24 of the angle member 30 which extends across the butt joint 16.

The puff 22 is preferably of soft, downy material particularly on its lower surface 26 while the remainder of the main body thereof may be of more durable texture as will be apparent.

The base 14 is provided with an inner liner or pan 32 which is adapted to contain the cosmetic, such as face powder in a loose form. The pan 32 fits closely rotatably within the base 14 and is provided with a cupped edge 34 the outer surface of which closely engages the inner side surface of the cupped base 14.

In the pan 32 are a plurality of scraper members which, in the instance illustrated, are formed from a pair of separate strips each having arms 38-38 at substantially right angles to each other. The arms 38 may abut at the center of the pan 32 as shown in Fig. 2 and they may be fixed to the floor of the pan by flange parts 40-40 of the strips.

The individual arms 38 may be slightly curved at their outer ends, as at 42, and they are of a width such that their upper edges project into and are adapted to rub along the

downy surface 26 of the powder puff 22 whenever the pan is rotated.

A suitable handle member 48 is provided for rotating the pan and this comprises a flat plate extending below the base 14 and having a circular center portion 50 and an integral upturned finger grip portion 52 at one side of the base.

The center portion 50 of the handle has a raised portion 54 which projects into an opening 56 formed through the bottom wall of the base and abuts the underside of the pan.

The handle 48 and the scraper arms 38 may be secured to the pan 32 as by the rivets 58 or in any other desired manner.

In use the vanity case may first be turned so that the base 14 is uppermost. This will insure the powder in the base 14 coming into contact with the downy surface 26 of the puff 22.

It will be appreciated that different users of cosmetics desire different amounts of powder on the puff according to individual taste. Accordingly, the case may now be reversed to bring the lid 10 uppermost, and the handle 48 may be operated to rotate the arms 38 for thereby scraping off from the downy surface of the puff a certain proportion of the powder adhering thereto. The amount of powder remaining will depend upon the amount of rotation of the arm.

The lid may then be opened and the puff removed from the case to apply the powder in the usual way.

It will be readily seen that each individual user of the device may obtain from the case a powder puff containing the quantity of powder desired and that this quantity may always be practically the same providing similar scraping action is performed in each instance.

It will also be seen that familiarity with the use of the device will lead to the correct amount of powder being obtained each time and that such familiarity, in view of the simplicity of the operation, will readily be reached.

An important characteristic of the device as disclosed herein resides in the fact that the loose powder contained within the pan 32 is so retained that there will be little likelihood of any part thereof leaking out of the pan or even of getting onto the surface of the mirror 18 when the case is closed. The pan which contains the powder is a complete and efficient carrier therefor. It has no bottom openings through which the powder could leak, and its upturned marginal wall or flange definitely confines the powder and fits so closely to the inner annular surface of the base 14 that there is scant likelihood of any of the powder ever finding its way downwardly between the bottom wall of the pan and the bottom wall of the base where it must needs go before it can possibly move through the pivot opening 56

in the bottom of the base. Even if any powder should find its way downwardly between the bottom wall of the pan and the bottom wall of the base, the rotary movement of the pan would produce such a divergent, or centrifugal, effect upon it that it would be more likely to move outwardly away from the pivot opening than toward the pivot opening.

The powder can not move upwardly onto the upper surface of the puff or onto the face of the mirror when the case is closed because at this time the puff itself constitutes a sealing gasket over the top of the pan, it being noted that the entire marginal edge portion of the puff is clamped tightly between the annular member 20 of the lid and the inwardly projecting leg 23 of the angle member 30 of the base.

If desired the sealing effect of the puff may be made more efficient by having either or both of the members 20 or 23 formed with one or more annular ribs thereon adapted to bite into the material of the puff, one such annular rib, as 59, being illustrated in the drawing as being formed upon the member 20.

The frictional engagement of the pan and handle with the base may be sufficient to retain these elements against unintentional movement, but if desired additional means may be provided and to this end the drawing suggests the provision of a relatively raised portion as 60 upon the base disposed so as to be engaged by the finger grip portion 52 of the handle, it being noted that this finger grip portion has a certain degree of resiliency adapting it to spring slightly when forced into engagement with the portion 60, thereby generating an amply tight frictional grip to retain the handle removably in a normal position with the finger grip resting against the portion 60.

Any suitable means may be employed for retaining the cover in a normal closed position and for this purpose the drawing suggests a slight protuberance as 61 formed upon the upstanding leg 24 of the angle member 30 and a corresponding slight recess 62 formed upon the telescoping portion of the lid so that these parts may snap into and out of retaining position in a well understood manner, it being obvious of course that the parts concerned have ample resilience to permit of this action.

As many changes could be made in this construction without departing from the scope of the invention, as defined in the following claims, it is intended that all matter contained in the above description, or shown in the accompanying drawing, shall be interpreted as illustrative only and not in a limiting sense.

The purpose of curving the arms 38 as above referred to, is to cause a certain degree of circular movement, or agitation, of the

powder which is confined within the separate compartments 63—63 they define. As the pan is rotated in one direction, as counter-clockwise in Fig. 2, the portion of powder engaging the arms will be wedged or urged relatively outwardly away from the center of the pan, due to the outwardly receding curvature of the arms, and of course the whole body of powder within the respective compartments will move around to replace that which is being moved outwardly. This movement will be particularly pronounced when the case is in its inverted position so that the powder rests upon the non-rotating surface of the puff 22, and the degree or speed of movement will depend largely upon the degree of curvature of the arms, as will be readily understood.

When the pan is rotated in the opposite direction the amount of the powder within the respective compartments will of course be reversed.

If desired the finger grip portion 52 may be extended upwardly and turned inwardly at its upper end so as to provide a downwardly facing ledge 65 at said upper end adapted when the handle is in engagement with the member 60 to overlie an upwardly facing ledge 66 of the lid portion of the device and thus constitute a latch for holding the lid portion more positively against accidental opening. It is simply necessary to swing the finger grip portion to one side or the other of the ledge 66 to disengage thereof for permitting the opening of the lid.

In some instances the ledge 65 may be formed with a slight protuberance as 67 thereon for snapping into a central seat as 68 provided to receive it in the ledge 66, thus to hold the finger grip portion against accidental movement out of engagement with the lid. It will be understood that the resilience of the finger grip portion provides a proper snap engagement of the elements 67 and 68.

If desired a pair of projections as 69 and 70 may be provided at opposite sides of the base of the device for limiting the swinging movement of the finger grip portion and hence also of the pan 32.

Having thus described my invention, what I claim as new and desire to secure by Letters Patent is:—

1. In a vanity case, a container for cosmetic, a puff in the container adapted to receive cosmetic, and means movably mounted within the container constituting a scraper movable to scrape off a portion of the cosmetic from the surface of the puff.

2. In a vanity case, a container for cosmetic, a puff in the container adapted to receive cosmetic on one surface thereof, and means movable across said surface to determine the quantity of cosmetic present

3. In a vanity case, a container for cosmetic, a puff in the container adapted to receive cosmetic on one surface thereof, scraper members in the container and engaging said surface of the puff, and means operable from the exterior of the container to move said scraper across said surface to determine the quantity of cosmetic present thereon.

4. In a vanity case, a base member having cupped edges thereon, a closure member having cupped edges abutting the edges of said base, means projecting from the base across the abutting edges and into the closure member to seal said edges, a pan in the base adapted to contain cosmetic, a puff supported by said mentioned means to receive cosmetic from the pan, and means co-operative with the puff to determine the quantity of cosmetic received thereby including a scraper within the pan arranged to scrape cosmetic from the surface of the puff.

5. In a vanity case, a base member adapted to contain cosmetic, a puff arranged to receive cosmetic from the base member on one surface of the puff, scraper members carried by the base member and engaging said surface of the puff, and means operable from the exterior of the base to move said scraper members across the surface of the puff to determine the quantity of cosmetic present thereon.

6. In a vanity case, a base member adapted to contain cosmetic, a puff arranged to receive cosmetic from the base member on one surface of the puff, scraper members carried by the base member and engaging said surface of the puff, and means operable from the exterior of the base member to move said scraper members across the surface of the puff to determine the quantity of cosmetic present thereon, said last means comprising a part extending across the base member beyond the center thereof and having an upturned edge at one side of said base member, means to secure the scraper members to the plate, and the upturned edge of the plate constituting finger-grip means whereby the scraper members may be moved.

7. A vanity case comprising a base member and a closure member pivotally connected together, the base member being adapted to contain a quantity of loose powder, a powder puff arranged to overlie said powder, and said base member and said closure member having parts co-operative when the case is closed to grip the powder puff and hold said powder puff as a sealing gasket against displacement of the powder.

8. A vanity case comprising a base member and a closure member pivotally connected together, the base member being adapted to contain a quantity of loose powder, a powder puff arranged to overlie said powder, and said base member and said closure member having parts co-operative when the case is

closed to grip the powder puff and hold said powder puff as a sealing gasket against displacement of the powder, together with a movable container for the powder whereby 5 to move the powder with respect to the powder puff, and means by which to move said powder container from without the base.

9. A vanity case comprising a base member and a closure member pivotally connected together, the base member being adapted 10 to contain a quantity of loose powder, a powder puff arranged to overlie said powder, and said base member and said closure member having parts co-operative when the base is 15 closed to grip the powder puff and hold said powder puff as a sealing gasket against displacement of the powder, together with a movable container for the powder whereby to move the powder with respect to the powder puff, means by which to move said powder container from without the case, and means to hold the container against unintentional movement.

10. In a vanity case, a container for cosmetic, a puff in the container adapted to receive cosmetic on one surface thereof, scraper members in the container radiating from the central portion of the container and engaging said surface of the puff, and means to swing said scraper members about said surface.

11. A vanity case comprising a base member, a closure member, the base member having a plurality of radially extending arms therein dividing the base into a plurality of 35 separate compartments each adapted to contain a quantity of loose powder, a powder puff arranged to overlie said compartments in engagement with said arms so as to receive powder from said compartments, means 40 to swing said arms about a common center at the center of said puff so as to scrape along the surface of the puff, and said arms being curved radially for the purpose set forth.

12. In a vanity case, a container for cosmetic, a puff in the container adapted to receive cosmetic on one surface thereof, scraper means, and means to cause relative movement of the scraper means across said surface of the puff to thereby determine the quantity of 45 cosmetic present upon said surface.

13. In a vanity case, a base member adapted to contain cosmetic, a puff arranged to receive cosmetic from the base member on one surface of the puff, scraper members carried 55 by the base member and engaging said surface of the puff, and means operable to move said scraper members across the surface of the puff to determine the quantity of cosmetic present thereon.

14. In a vanity case, a base member adapted to contain cosmetic, a puff arranged to receive cosmetic from the base member on one surface of the puff, scraper members carried 60 by the base member and engaging said surface of the puff, and means operable from the ex-

terior of the base member to move said scraper members across the surface of the puff to determine the quantity of cosmetic present thereon, said last means comprising a part 70 fixed to said scraper members and projecting through an opening of the base member said part having a portion extending to the marginal edge of the base member and there providing a finger grip by which to move said part.

15. In a vanity case, a base member adapted to contain cosmetic, a puff arranged to receive cosmetic from the base member on one surface of the puff, scraper members carried by the base member and engaging said surface of the puff, and means operable from the exterior of the base member to move said scraper members across the surface of the puff to determine the quantity of cosmetic present thereon, said last means comprising a part fixed to 80 said scraper members and projecting through an opening formed through a wall of the base member and to a position of accessibility exteriorly of the base member.

16. In a vanity case, a container, a pan 90 rotatably mounted within the container adapted to contain a quantity of cosmetic, a non-rotatable puff support also within the container, a puff supported by said puff support, means comprised in the container movable into and out of position holding the puff stationary with said puff support, and means by which to rotate the pan for applying cosmetic to the stationary puff.

Signed at New York, in the county of New York and State of New York, this 25th day of September, 1931.

HAROLD BATCHELOR.
